UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

MULTIPLE-PLY WEB FOR TYPEWRITERS.

1,400,631.

Specification of Letters Patent. Patented Dec. 20, 1921.

Application filed July 20, 1918. Serial No. 245,810.

To all whom it may concern:

Be it known that I, JESSE A. B. SMITH, a citizen of the United States, residing in Stamford, in the county of Fairfield and 3 State of Connecticut, have invented certain new and useful Improvements in Multiple-Ply Webs for Typewriters, of which the following is a specification.

This invention relates to superposed or 10 multiple-ply work webs for use in typewriting machines, as for example in the class of machines illustrated in the patent to Wernery and Smith, No. 1,132,055, in which the carbon sheets inserted between 15 the webs or plies are shifted backwardly at intervals, preparatory to typing fresh portions of the webs or plies.

In said patent, there is illustrated a single-piece web which is folded longitudinally in zigzag fashion, making what is 20 known as a fan-fold web. An objection that has arisen to the use of this web for some purposes, is that if the grade of paper be high enough for sending out to customers, 25 it is too expensive to use for office purposes; it being usually desired to send the ink-ribbon copy to the customer, and to retain the carbon copies for office filing and other uses. Moreover, if the grade of paper is 30 high, it is usually of such heavy quality that a large number of copies cannot be clearly manifolded. If the paper used is thin, for manifolding, and of a low grade, for economy, it does not prove suitable to 35 send out to customers. In other words, the same paper that is used for one purpose, must be used for all purposes; and frequently it is found to be either too expensive for one purpose or too poor for another 40 purpose. Again, it is desired to have certain of the plies of different color from others, and this has heretofore been accomplished in an inexpensive way by printing a color stripe upon a portion of the broad web 45 as it passes through the printing press preparatory to being fan-folded. Still other methods have been proposed for overcoming the foregoing and other difficulties attendant upon the use of the fan-fold web, but 50 in practice the field for use of such web has been limited, thereby narrowing the market for typewriting machines adapted to handle this class of work.

Prior to said Wernery and Smith inven-

tion, there were attempts to use superposed 55 separate webs or plies of paper fed into the machine from spools; and since the date of said invention, various efforts have been made to adapt the separate web method to the Wernery and Smith machine, so as to 60 permit the use of superposed webs or plies of different colors and qualities, but all 65 printed with a succession of similar or complementary forms. But the trouble has been encountered, that owing to the feeding of 70 the superposed webs around the cylindrical platen of the typewriting machine, there occurs relative creeping of the webs upon one another, this creeping being cumulative, so 75 that after several forms have been typed, the forms on the several webs are found to be out of register with one another, so that words typed in their proper places upon one web or ply will fall out of place upon underlying webs or plies. To overcome this 80 difficulty, several proposals have been made, one of which is to provide impaling pins upon the typewriting machine, and to form corresponding re-registering holes in all of the forms in all of the webs, thereby 85 enabling the operator to re-register the webs preparatory to the typing of each form. This, of course, calls for additional work and attention on the part of the operator, and the holes in the paper which are 90 apt to prove unsightly and objectionable, particularly in the sheets which are to be sent out to the customers. Furthermore, the holes have to be large, and necessarily extra paper has to be provided or allowed on 95 each form to accommodate these holes, and this adds substantially to the expense of the paper and to the bulkiness of the copies intended for filing.

The object of the present invention, therefore, is to provide a way whereby superposed plies or webs of different qualities and often of different colors, may be employed without incurring the described trouble of relative creeping among the several webs or plies, and without the necessity of punching objectionable re-registering holes in the webs, or of providing extra paper which the use of such holes necessitates.

In practising the preferred manner of manufacturing a composite product to be used in a typewriting machine, the separate

single-ply webs, of a variety of colors and grades, may be printed simultaneously in the same printing press, in such a manner that the forms printed upon the various webs 5 register accurately with one another, and while such registry is maintained, the edges of the webs are padded together, preferably by means of an adhesive material, any well-known padding paste or glue being suitable 10 for this purpose, especially of the kind which is elastic when dry. Rubber cement may be used in some cases; the elasticity of this or other adhesive materials being of an advantage to permit the padded web to pass 15 readily around the platen or rolls of the typewriting machine.

The adhesive material may be applied in any suitable way, as, for example, by means of a brush or roll which may be supplied 20 with adhesive material from a font. After the application of the adhesive material, the assembled webs or plies may be run through pressure rolls to press them together along the line of adhesive material, 25 and these rolls may, if desired, be heated so as to facilitate the drying of the adhesive material.

Preferably the web with a single set of edges thus padded together is permitted to 30 dry before leaving the apparatus, and, for this purpose, the web may be led up and over a roll and then allowed to fall and to form a loop, the web running up over a second roll, and so on, there being as many 35 rolls and loops as desired, so as to secure the needed time for drying. These looping rolls may be inclosed in an oven or drying closet. The drying rolls may be driven at suitable speed, being prefer- 40 ably connected to the printing press so as to secure an accurate timing of the rolls. From the drying closet, the composite web may be led into a suitable coiler, by which the web may be given preferably a zigzag cross-fold, whereby it is compacted into a package suitable for marketing.

Such a web may be readily led through either the typewriting machine disclosed in said Wernery and Smith patent, or through 50 other varieties of typewriting machines, and the successive forms may be torn off after typing, and there will be no difficulty experienced from accumulation of creep along the webs, since, when a portion is torn off, 55 the remainder of the padded web remains in its original registered condition, and hence no re-registry of the plies or webs among themselves is at any time necessary, nor is it necessary to form unsightly registering holes therein, or to provide extra paper to accommodate the holes; while each of the various plies may be of any desired grade or color independently of the others.

Other features and advantages will here-
; inafter appear.

In the accompanying drawings,

Figure 1 is a diagrammatic side elevation of the multiple printing press and padding, drying and coiling apparatus.

Fig. 2 is a perspective view of a portion 70 of the devices seen in Fig. 1.

Fig. 3 is a perspective view of a fragment of the product.

Fig. 4 is a side elevation on a small scale 75 of another form of padding and drying apparatus.

The webs or plies 10, 11, 12, 13, of which four are illustrated, although the product may comprise less or more than four webs, are passed simultaneously through a print- 80 ing press comprising printing couples 14, whereby successive forms 15 are printed upon the webs, with the forms upon each web registering with those upon the other webs. From the printing press the webs 85 are led on to a padding apparatus, which superposes and pads the webs together while they remain in exact registry from the print- 90 ing press. Preferably, the composite web is padded along only one edge at 16, Fig. 90 3, so that it may open out at the opposite edge for conveniently inserting the carbons.

To illustrate one method of padding or catching the plies together, there is shown a roll 17 for applying adhesive material 18 95 to the edges of the plies. This roll 17 may run in an aperture 19 in the bottom of a font 20 in which the adhesive material 18 may be placed, and this font and roll may be provided with any suitable heating 100 device, for keeping the paste or adhesive material in proper fluent condition. In carrying out the invention in one way, the adhesive material may be applied only to the inner plies 11 and 12, as at Figs. 1 and 2, 105 the roll being made too thin to reach the outer plies 10 and 13. All of the plies at this stage are seen converging toward the feed-rolls 21 below the font of adhesive material; suitable guide-rolls 22, over which the plies bend, being provided between the printing press and the adhesive-material- 110 applying roll 17. As the plies contact, the adhesive material sticks all four plies together. The feed-rolls 21 may, if desired, 115 be of sufficient length to press the plies together at their adhesive edges, to make the adhesion more firm; and, if desired, the rolls 21, 22, etc., may be heated, to hasten the dry- 120 ing of the adhesive material. It will be understood that the feed-rolls 21 need not be long enough to reach the pasted edges, and hence that the adhesive material may remain only upon the extreme edge of the composite web and not tend to spread across 125 the faces of the plies, so that, after the web has been typed, the plies may be easily separated one from another.

However, if the feed-rolls 21 are used to press the pasted edges of the webs together,

stationary stripping or cleaning knives 23 may be used for keeping the rolls clean from adhesive material; and, if desired, one or more couples of additional heating and feeding rolls 24 may be provided below the feed-rolls already mentioned. All of the driving rolls 21, 24, etc., may be suitably connected with the printing couples of the printing press, to secure proper speed of the composite web as it feeds through the padding and coiling apparatus.

To facilitate the drying of the padded web 25, it may be led under a guide-bar or roll 26 and looped up over a feed-roll 27, and then may be allowed to drop to form a second loop 28, whence it may rise to pass over a second feed-roll 29; and in this manner as many more loops as desired may be formed, by providing an additional feed-roll for each loop. These feed-rolls may coöperate with pressure-rolls 30, and may be connected to the rolls of the printing press so as to give the requisite speed to the composite web 25 as it travels up and down the loops. The loops may be contained in a heated oven or drying closet 31, and the web may be passed around a roll 32 and led out from said closet and between suitable feeding rolls 33 to a zigzag cross-folding device 34, which may be of any suitable or known construction and operation, and thereby the padded web may be finally coiled or compacted into a package 35 convenient for marketing.

In use, the web may be placed in a box which may rest upon the floor close to the stand which supports the typewriting machine, and the web may be led up in open condition from said box to the typewriting machine; the thinness of the composite padded web and the elasticity of the dried adhesive material permitting the web to pass freely around the rolls of the typewriting machine. The invention may be carried out in various ways, and is not limited to the precise method of padding or the precise product herein described by way of illustration; the principle of the invention being the padding of plies of web, which is coiled or reduced to a condition to be marketed in compact and available form.

In practising the invention in the manner shown in Fig. 4, the webs, in passing from the printing couples 14 of the press, are assembled between feed-rolls 36 and pass down until their edges come in contact with a pasting roll 37, below which is arranged a couple of rolls 21 corresponding to the rolls seen in Fig. 1; and, in place of looping the padded web 25 up and down, as seen in Fig. 1, it is carried to and fro horizontally upon endless traveling belts 38, 39, arranged in a heated drying oven or closet 40; the belts connected to run alternately in opposite directions, so that the web 25 runs to and fro

in a zigzag path; suitable connections being made from the printing press rolls to the rolls 38^a which carry the endless belts. From this drying closet 40, the web is led over feeding rolls 41 to a zigzag cross-folder 70 34 to produce the coiled product.

Variations may be resorted to within the scope of the invention, and portions of the improvements may be used without others.

Having thus described my invention, I 75 claim:

1. A new article of manufacture, consisting of a web having a succession of registering forms printed thereon, with the lines reading across the web and comprising numerous plies padded together at one edge to form a unitary composite web, said plies being of different characteristics, and said web forming a package having numerous layers in compact form for feeding into a 85 typewriting machine.

2. A new article of manufacture, consisting of a web having a succession of registering forms printed thereon and comprising plies whose edges are padded together to 90 form a unitary composite web, said plies having differing characteristics, and said web forming a package having numerous layers in compact form for feeding into a typewriting machine, said plies being 95 padded together by an adhesive material sufficiently elastic to permit the opening of the web from its compact condition and also to permit the web to pass readily around the rolls of the typewriting machine. 100

3. A new article of manufacture, consisting of a web having a succession of registering forms printed thereon and comprising plies whose edges are padded together to form a unitary composite web, said plies 105 having differing characteristics, and said web forming a package having numerous layers in compact zigzag cross-folded form, and said plies being padded together by an adhesive material sufficiently elastic to permit the opening of the web from its compact condition and also to permit the web to pass readily around the rolls of the typewriting machine. 110

4. A new article of manufacture consisting of a web having a succession of registering forms printed thereon, with the lines reading across the web and comprising plies whose edges are padded together to form a unitary composite web, said plies having dif- 120 fering characteristics, and said web forming a package having numerous layers in compact form for feeding into a typewriting machine, said web consisting of a plurality of single plies; elastic padding material 125 joining their edges along only one side of the web.

5. A new article of manufacture, consisting of a web having a succession of registering forms printed thereon and comprising 130

plies padded together at one edge to form a unitary composite web, said plies being of different characteristics, and the padding of said plies being flexible to permit the opening of the web and to permit the padded plies to be bent readily to permit packing of the web in compact condition, and also to permit the web to pass readily around the rolls of a typewriting machine.
